CLAIM

The ornamental design for a headset, as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a left side view thereof; and,

FIG. 6 is a right side view thereof.

The dashed broken lines in the figures show portions of the headset that form no part of the claimed design.

The dot-dash broken lines in the figures show unclaimed boundaries of claimed portions of the design.

1 Claim, 6 Drawing Sheets
